CLAIM

The ornamental design for a smoking cone, as shown and described.

DESCRIPTION

FIG. 1 is a right side perspective view of a smoking cone showing my new design;

FIG. 2 is a right side elevation view thereof;

FIG. 3 is a back end elevation view thereof; and,

FIG. 4 is a front end elevation view thereof.

The left side elevation view is a mirror image of the right side elevation view of FIG. 2, and is therefore not illustrated in the drawing disclosure.

The top plan view and the bottom plan view are the same as FIG. 2, and are therefore not illustrated in the drawing disclosure.

Where included, the solid black surface shading represents a color contrast, but does not represent any particular color, material, texture, or finish, and no specific colors are hereby claimed.

Where included, the use of stippling and straight line shading is provided to show contrast in materials and/or to differentiate between different areas of the design.

The broken lines represent internal bounds of the claimed design that form no part of the claimed design.
